UNITED STATES PATENT OFFICE.

SILAS B. BROWN, OF CINCINNATI, OHIO, ASSIGNOR TO THE EDWARDS MANUFACTURING COMPANY, OF CINCINNATI, OHIO, A CORPORATION OF OHIO.

TOY PISTOL.

Application filed June 30, 1921. Serial No. 481,722.

To all whom it may concern:

Be it known that I, SILAS B. BROWN, a citizen of the United States, and residing at Cincinnati, in the county of Hamilton and 5 State of Ohio, have invented a new and useful Improvement in Toy Pistols, of which the following specification is a full disclosure.

My invention relates to a toy pistol of a 10 type adapted to explode caps of a roll of conventional ammunition tape. An object of the invention is to provide a toy which will faithfully simulate a modern automatic firearm—the caps being exploded 15 internally of the pistol casing, combustion products escaping through the barrel. Another object of the invention is to very materially improve the tape feed and controlling mechanism, but more partic- 20 ularly the mechanism is devised to accurately and invariably feed the cap to a pre- determined position on the anvil. A portion of the hammer acts to protect the next adjacent cap to be fired from the back-fire 25 of the exploding cap. The hammer also acts against an anvil strip to prevent back- lash of the tape, when the tape feed pawl recedes. The feed mechanism is so organized as to insure the feed pawl always op- 30 erably engaging with the tape just in rear of the caps. Another object of the invention is to eliminate from the combination the ordinary guide and backlash spring heretofore employed. Another object of the in- 35 vention is to provide an improved frame construction adapted for convenient assembly of the operating mechanism. Another ob- ject of the invention is to very greatly sim- plify the construction and arrangement of 40 the parts.

The detail escapement for the hammer- trigger mechanism is also a feature of the improvement. Another object of the improvement is to provide means whereby the 45 engaging end of the feed pawl is normally supported upon a frame member out of contact with the ammunition tape, and only moved into feed contact therewith when the trigger is operated. Other features and ob- 50 jects of the invention will appear in connec- tion with the description of combination drawings forming a part of this specification, wherein:—

Fig. 1 is an elevation of my improved pis- 55 tol, the side to which the mechanism is at-

tached, being broken away to more clearly show said mechanism.

Fig. 2 is a front cross sectional view of the mechanism.

Fig. 3 is a rear cross sectional view of the 60 mechanism.

Fig. 4 is a section on line 4, 4, of Fig. 1, illustrating the relation of the actuating portions of the trigger and hammer in their initial positions.

Fig. 5 is a detail side elevation of the ham- 65 mer.

Fig. 6 is an end view of the same.

Fig. 7 is a fragmentary detail elevation 70 of the trigger.

Fig. 8 is a section on line 8, 8, of Fig. 7.

Figs. 9, 10, 11 and 12, are diagrammatic 75 views showing successive tape-feed opera- tions.

Fig. 13 is a view of the skeleton frame.

The pistol shell or casing is composed of two sheet metal members forming a housing, hinged at the top or upper barrel margin 60, the margins 70, at the bottom edges of the butt are detachably snapped together to 80 close the pistol casing. It is only necessary to show one of these shell members, and accordingly I have shown in Fig. 1 the shell member 1, providing a supporting pin 2, for the ammunition roll 3, and it also is formed 85 with apertures designed to register with cer- tain of the frame projections to support and secure the frame, the hammer, and trigger fulcrum posts providing two of said pro- jections.

The assembly frame is of skeleton form (see Fig. 13) having the upper anvil mem- 90 ber 4, and side frame section integral therewith, comprising section 5, extending rear- wardly from the anvil and upon which, in rear of the anvil section 4, and spaced verti- 95 cally and horizontally therefrom, is a hori- zontally extended shoulder 6, (see Fig. 9). The side portion of the frame is completed by the two downwardly extended members 100 7 and 8, and bottom horizontal member 9, connecting members 7 and 8, and providing a frame having only one side member upon which the pistol parts are to be assembled, the other or open side of which is to be 105 closed, and supported by the shell mem- ber.

Laterally projecting from the lower side frame portion are two horizontal spacing and spring tension sustaining posts 10, 11, 110

which rest against the shell casing 1 when the pistol is assembled. There are also formed on said side portion of the frame, trigger and hammer fulcrum posts 12, 13, respectively, the free ends being riveted to and supported by said casing member.

An important structural and functional characteristic of the improvement lies in the formation of the interior under surface of the anvil member 4 of the frame, wherein there is an anvil formation 14, in registration with the hammer, the member 5 in rear thereof having a cut out portion 15, at the rear end of which is formed a depending abutment lug 16. The member 5 in rear of lug 16 is also formed with a cut away portion 17 providing a tape-entering throat in spaced relation with abutment shoulder 6.

To the front end of member 5 is secured a resilient anvil strip 18, rearwardly extended beyond member 5, and occupying a position between the hammer and anvil and between the rear end of the anvil member 5, and shoulder 6, the rear end of this strip 5 being upturned for a finger grasp. This is really an anvil covering strip whose functions are determined by its relationship to the anvil, hammer, lug 16 and shoulder 6, and cut away formations 15, 17, and it is 0 actuated to perform these functions by the pressure of the feed pawl 19.

It will be seen that the space between the adjacent margins of the member 5 and shoulder 6, form a throat for introducing the ammunition tape. In normal position the end of the anvil strip 18 is above and out of contact with the shoulder 6, enabling the tape to be threaded under the spring 18 through the clearance provided by cut out portion 17, and into position for operative control by the tape feed mechanism, i. e. the feed pawl 19 and anvil strip 18. The upper surface of shoulder 6 forms a rigid support for the tape, furthering its 5 accurate delivery into the next position with respect to the pawl feed and anvil spring.

Upon the hammer fulcrum post 13 of this frame is placed the hammer 20, held normally against the anvil by spring 21. In 0 rear of the exploding head of the hammer there is a V-like notch providing an upwardly projecting detent 22, which when the tape is in firing position impinges against the tape and anvil spring 18 just 5 in rear of the anvil upon that yielding portion of spring 18, which bridges the lug 16 and the anvil formation 14 of member 5. This detent acting against the spring resilience at this point, and impinging the tape, 0 prevents backlash and also constitutes a barrier between the forward cap 23 upon the anvil, and the next cap 24 at the rear, preventing any back-fire, and as stated, serving to prevent any backlash of the tape when 5 the feed pawl 19 is returned to normal po-

sition. This hammer is provided with an extension 25 below the fulcrum for cooperation with the trigger.

Further, it is quite important that the hammer head, directly in front of the detent 22, be formed with a downwardly extending vent 40, (see Fig. 1) opening into the interior of the frame, for the escape of gases, preventing the escaping gases when exploding from reacting upon the hammer, 75 or upon the sensitive anvil spring 18 adjacent the anvil.

Trigger 26 is mounted on fulcrum post 12, and is held in normal initial position by coil spring 27, having a rearwardly extending terminal end 28 for engaging and influencing the feed pawl 19.

Said trigger 26 has an extension member 29 rearwardly of the fulcrum, having a notch 30, upon which is pivotally mounted 85 a ratchet feed pawl 19, formed with an aperture 31, through which passes the said terminal end 28, of the trigger spring, the feed engaging end of the pawl resting normally on the under forward surface of the shoulder 6, free from any impingement engagement with the tape, but in position to move forward with the trigger and engage the tape.

The normal position of the mechanism is 95 indicated in Fig. 1, wherein the tape has been loosely inserted through the throat 17 and lies against the spring 18. The initial movement of the trigger moves the feed pawl to a position shown in Fig. 9, wherein the 100 hammer is slightly raised from the anvil, and the pawl slightly engages the tape.

As shown in Fig. 10, further movement deflects the spring 18 and the pawl takes firm hold upon the tape. As the pawl moves 105 forwardly from its position, shown in Fig. 10, and passes beyond the lug 16, and as the angle between the pawl and tape becomes more acute, and because of the rounded engaging edge 19^a of the pawl, the same slips 110 along the tape, as shown in Fig. 11, to engage the cap 24, the spring 18 having been deflected to swing its rear end toward the shoulder 6, thus imposing a slight tension upon the tape by pressing it towards and 115 against said shoulder, to form a brake upon the tape while the pawl slips to cap-engagement. Further movement of the pawl to its limit of movement positions the cap 23 in firing position upon the anvil 14 and immediately thereafter the same is fired.

Inasmuch as the pawl, after having passed the lug 16, is capable of being disengaged from the strip to slide forwardly to engage the cap, and inasmuch as the passage of the 125 pawl beyond said lug deflects the spring to form a brake for the tape, the accurate positioning of the forward cap 23 upon the anvil is assured. This structure has overcome all difficulties heretofore experienced 130

in an attempt to accurately and consecutively position said caps.

At the instant of explosion, (see Fig. 12), the hammer detent 22 acts as a barrier between the two forward caps, and at the same time, as explained, it impinges the tape against a yielding portion of the spring 18, throwing its outer end against the tape and so holds it in this position during the 10 turn of the pawl to initial position.

The hammer and trigger extensions 25, 29^a respectively, provide cams which operate in intersecting arcs, the camming formations constituting an escapement, enabling the 15 trigger to cock the hammer and release it for fire, the hammer and trigger returning to initial position independently. In this initial position, the member 29^a has a shoulder or cam surface 32, engaging with the 20 cam surface 33, of the extension 25, so that as the trigger moves, its surface 32 rides downwardly of the hammer cam surface 33 until the hammer is fully cocked, at which time the lower end of the cam 33 is opposite the release formation 34, of member 29^a, which allows the arm 25 to pass forwardly over the said member 29^a, thus allowing the hammer to snap to firing position.

It will be seen that the anvil spring, the 30 hammer and its spring, the trigger, its spring, and pawl feed, can be readily assembled in relation to this skeleton frame, and the assembly securance is completed by attaching this frame to the shell casing, the 35 pawl feed being the key of the assembly formation.

It will readily be seen how extremely simple and reduced in number are these parts, namely, the support frame comprising the 40 anvil and shoulder for entering the tape, the anvil spring, hammer and hammer spring, trigger and trigger spring and pawl, simply seven pieces.

Moreover, the frame and these parts can 45 be made of very small dimensions and of light metal or alloy admirably adapted for die casting the parts. The tape control, due to the unique movement of the spring 18 under the pressure influence of the feed 50 pawl, in relation to the abutments and cut-out sections provided by anvil member 4, is fully diagrammed in Figs. 9 to 12.

The great difficulty with previous devices of this kind has been the irregularity 55 of fire, due to the fact that no means were provided for giving the pawl a definite feed position in relation to the caps of the tape, and that the feed pawl is constantly impinging upon the tape.

60 As explained, the caps which are on the under side of the tape, virtually constitute ratchet teeth for the definite cooperation with the pawl.

It is obvious that a great many changes 65 could be made from the exact details of the

preferred embodiment illustrated, without a substantial departure from the teachings of this disclosure.

The spring 21 serves a two-fold function, that of swinging the hammer upon its axis 70 for forcibly striking the hammer head against the anvil 4 when the hammer, after being cocked, is released by the trigger, and for yieldingly sustaining the hammer against transverse movement upon its axis. 75

As shown in Fig. 2, the coil portion of the spring 21 is wound so as to be capable of compression bearing intermediately between the frames 1 and the hammer and about the hub extension of the latter. This prevents 80 the hammer from being shifted transversely upon its axis when its extension 25 engages the inclined surface 34 of the trigger for cocking release. This coil portion of the spring forces the hammer automatically into 85 its normal position for a subsequent trigger cooperation.

Having described my invention, I claim:

1. In a toy pistol, a frame providing an anvil member, a hammer, hammer and trigger operating mechanism, a tape-feeding pawl operated thereby when the hammer is cocked, and a flat spring secured to the anvil member forming an operative abutment for the pawl. 90

2. In a toy pistol, a frame formed with an anvil member, and a spaced tape support providing a tape entering aperture into the frame, a hammer, hammer and trigger operating mechanism, a tape-feeding rigid 100 pawl advancing when the hammer is cocked and spring-pressed toward the anvil member, the feed end normally engaging the under surface of said support, a flat spring secured to the anvil member, providing an 105 elastic abutment for the pawl in its movement, the anvil member having cut away sections, whereby the spring is deflected by the pawl in its movement to control the tape movement. 110

3. In a toy pistol, a frame formed with an anvil member and a spaced tape support, forming a shoulder and providing a tape entrance, a hammer, hammer and trigger operating mechanism, a rigid pawl feed 115 spring-pressed towards the anvil member, said member having an anvil proper and a rearward under cut extension, a flat spring secured over the anvil and cut-away extension, and terminating above and beyond said 120 shoulder, the pawl normally resting against the shoulder out of contact with said spring, leaving an open space to thread the tape without lifting the pawl and moving into contact therewith to deflect the spring and 125 definitely control the tape advance.

4. In a toy pistol, a frame formed with an anvil member and a spaced tape support, forming a shoulder and providing a tape entrance, a hammer, hammer, 130

and trigger operating mechanism, a rigid pawl feed spring-pressed towards the anvil member, said member having an anvil proper and a rearward under-cut extension, a flat spring secured over the anvil and cut-away extension, and terminating above and beyond said shoulder, the pawl normally resting against the shoulder out of contact with said spring, and moving into contact therewith to deflect the spring and definitely control the tape advance, and a detent on the hammer coating with a yielding portion of the anvil spring to prevent backlash and to act as a barrier between the cap on the anvil and an adjacent cap.

5. In a toy pistol, a frame formed with an anvil member and a spaced tape support, forming a shoulder and providing a tape entrance, a hammer, hammer and trigger operating mechanism, a rigid pawl feed spring-pressed towards the anvil member, said member having an anvil proper and a rearward under-cut extension, a flat spring secured over the anvil and cut-away extension, and terminating above and beyond said shoulder, the pawl normally resting against the shoulder out of contact with said spring, and moving into contact therewith to deflect the spring and definitely control the tape advance, and a detent on the hammer coating with a yielding portion of the anvil spring to prevent backlash and to act as a barrier between the cap on the anvil and an adjacent cap, said hammer head being formed with a gas vent into the frame.

6. In a toy pistol, a frame formed with an anvil member and rearward extension, and a tape support shoulder forming a tape entrance adjacent the anvil extension, a flat spring for the anvil and extension, having its free end projecting through said tape entrance, a hammer and spring, a trigger and spring, self-cocking connections, a trigger extension, a rigid tape feeding pawl therein engaging and held by the trigger spring, the free end of the pawl normally resting against the tape support, and moving forward with the trigger, to press the tape against the anvil spring, means on the anvil extension enabling the spring to be deflected by the pawl movement to operatively position the pawl in relation to a cap formation of the tape.

7. In a toy pistol a frame providing an anvil having a rearward extension and a shoulder providing a tape support and entrance adjacent the anvil extension, a flat spring secured to the anvil end, having its free end adjacent to said shoulder, trigger and hammer mechanism, and a tape feed actuated thereby and coordinating with said spring to control the tape movement.

8. In a toy pistol, a frame providing an anvil having a rearward extension and a shoulder providing a tape support and en-

trance adjacent the anvil extension, a flat spring secured to the anvil and having its free end adjacent said shoulder, trigger and hammer mechanism, and a tape feed actuated thereby and coordinating with said spring to control the tape movement, and a detent on the hammer engaging said spring in rear of the anvil.

9. In a toy pistol, a frame providing an anvil having a rearward extension and a shoulder providing a tape support and entrance adjacent the anvil extension, a flat spring secured to the anvil and having its free end adjacent said shoulder, trigger and hammer mechanism, and a tape feed actuated thereby and coordinately with said spring to control the tape movement, and a detent on the hammer engaging said spring in rear of the anvil, said anvil extension being under cut adjacent said pawl portion of movement and said hammer detent.

10. In a toy pistol, a frame providing an anvil having a rearward extension, and an abutment forming a tape support and entrance, a flat spring for said anvil and extension positioned with its free end in said tape entrance, hammer and trigger mechanism, a tape-feeding pawl actuated thereby and coordinating with said abutment and anvil spring.

11. In a toy pistol, a frame, an anvil member, a tape support adjacent the anvil presenting a tape entrance, an anvil spring extended into said entrance, trigger and hammer mechanism, a pawl feed cooperating with the support and said anvil spring, the hammer formed with a detent adjacent the anvil, and with a vent for escaping gases adjacent the anvil.

12. In a toy pistol, a frame, a hammer and trigger mechanism and springs supported therein, a rearward trigger extension, a pawl tape feed on the trigger extension engaging the trigger spring, said frame providing an extended anvil member superposed in relation to the hammer and pawl feed, a frame abutment spaced from the anvil member providing a tape support and entrance, and a flat spring secured to and extending along the anvil member to abut the hammer and pawl feed, and having its free end extended into said tape entrance.

13. In a toy pistol, a frame, a hammer and trigger mechanism and springs supported therein, a rearward trigger extension, a pawl tape feed on the trigger extension engaging the trigger spring, said frame providing an extended anvil member superposed in relation to the hammer and pawl feed, a frame abutment spaced from the anvil member providing a tape support and entrance, and a flat spring secured to and extending along the anvil member to abut the hammer and pawl feed, and having

its free end extended into said tape entrance, said anvil member in rear of the anvil being formed with under cuts enabling the spring to be deflected by the pawl 5 movement and said hammer being formed with a tape-engaging detent impinging toward the spring in normal position.

In witness whereof, I hereunto subscribe my name, as attested by the two subscribing witnesses.
